MULTISTAGE WELL PUMP

John H. Puls, Los Angeles, Calif., assignor, by
mesne assignments, to The Texas Company,
New York, N. Y., a corporation of Delaware

Application April 8, 1941, Serial No. 387,399

3 Claims. (CL 103—187)

This invention relates to well pumps, and more particularly to a multi-stage pump of the working barrel type for pumping fluids such as mixtures of oil and gas.

The principal object of this invention is the provision of a pump of this type by means of which a fluid such as a mixture of oil and gas can be pumped upwardly in a well in a plurality of pressure stages and by means of which an improved volumetric efficiency, as well as an improved mechanical efficiency, will be obtained when pumping gaseous liquids. Other objects are to eliminate fluid pounding and the gas locking of well pumps, and thus increase the production from wells.

There are many oil wells which are capable of additional production of the order of from say 10 to 100 barrels per day each. However, it has heretofore been found impossible to attain this oil production rate due to the fact that the oil contains gas. In the past few years methods and apparatus have been developed for detecting and analyzing these wells, and various suggestions and methods have been proposed for overcoming the difficulties without appreciable success. Many types of gas anchors, more or less complicated in construction, have been tried in an effort to remove the gas from the oil before it reached the pump in the hole, but in many cases these gas anchors do not provide adequate separation of the gas from the oil. Other problems encountered in the pumping of gaseous liquids have been unsolved and, of these, fluid pounding and the gas locking of the pumps have perhaps been the most serious.

In accordance with the present invention, a pump has been devised by means of which the rate of production from a well can be greatly increased, the gas in the oil being compressed in two or more pressure stages so as to assist in the raising of the oil to the surface. In pumping a well at a depth of from say 6000' to 7000', pressures of around 2000# per sq. in. are usually encountered, and at the present time many single stage pumps are being used to furnish pressure of this and greater amounts in order to pump oil to the surface from a well of this depth. Obviously, this manner of raising oil is very inefficient. One would not think of compressing gas in a compressor to say 2000# in one stage and yet an oil pump is expected to do just that.

In carrying out the invention a pump has been provided having two or more stages of compression and in which a vertically reciprocable working barrel is actuated from the surface over a

stationary plunger having two or more fixed pistons. On the upstroke of the barrel the mixture of oil and gas is drawn upwardly through a standing valve into an annular chamber, while at the same time oil and gas previously compressed in a similar annular chamber is forced from that chamber into and upwardly through the fixed plunger, and thus upwardly to the surface. On the down-stroke oil and gas previously drawn into the first mentioned chamber is then squeezed into the second chamber through a valved passage in the fixed plunger. With this type of pump the working barrel may be reciprocated by means of ordinary sucker rods and the use of flow tubing is therefore rendered unnecessary.

For a better understanding of the invention reference may be had to the accompanying drawing in which:

20 Fig. 1 is a vertical sectional elevation through the lower portion of a well containing a two-stage pump embodying the invention

Fig. 2 is a similar view showing a three-stage pump, while

25 Fig. 3 is a detailed sectional elevation showing a modified form of standing valve containing means for relieving excessive pressures.

Referring to the drawing, a well 10 is shown as provided with a casing 12 and the lower portion of a string of tubing 14 containing a two-stage pump embodying this invention. The pump comprises essentially a stationary plunger 16 connected at its lower end by any suitable means such as a pump lock 18 to the lower end 30 of the tubing 14, and the vertical reciprocable working barrel 20 disposed in external sliding engagement with the fixed plunger. The barrel 20 can be reciprocated from the surface by any suitable means, such as a string of sucker rods 22, connected to the upper end of the working barrel by means of a suitable bonnet which allows the fluid to pass upwardly from the barrel into the interior of the tubing 14.

45 The stationary plunger 16 comprises a tubular member to which the reference character 16 has been applied and a pair of pistons 26 and 28 of a diameter such as to have a sliding fit within the working barrel 20. The working barrel is provided near its mid-point with an annular ring 30 formed integral with or attached to the inner surface of the barrel and having an internal diameter such that it will have sliding engagement with the tubular portion of the plunger 16.

50 It will thus be seen that the annular plunger or ring 30 in the working barrel divides the space

between two fixed plungers 26 and 28 into the two chambers 32 and 34. The tubular portions of the fixed plunger 16 is provided with sets of openings or ports 36 and 38 connecting the interior of the fixed plunger to the two chambers 32 and 34, respectively. The fixed plunger is also provided beyond and below the ports 36 and 38 with suitable valve seats with which valves 40 and 42, 44 and 46, are adapted to cooperate. The lowermost valve 40 can be considered the equivalent of the ordinary standing valve, and the purpose of the other valves will be brought out subsequently.

In operation, it will be noted that on the downstroke of the working barrel 20 the chamber 32 is becoming smaller while the chamber 34 is becoming larger, and a mixture of liquid, such as oil and gas previously trapped in the chamber 32, will be forced into the ports 36, into the plunger 16, upwardly past the valves 42 and 44 and through ports 38 into chamber 34. After the pump has been in operation for a few strokes a certain amount of gas will remain compressed in the chamber 32 and this will tend to force the oil with the remaining gas into the chamber 34 at a considerably higher pressure. This action therefore comprises the first stage of the compression. On the upstroke of the working barrel 20 the oil and gas fill the chamber between the ring 30 and the fixed piston 28 until the pressure is high enough to raise the valve 46 whereupon the oil and gas will pass upwardly through piston 28, the upper portion of the working barrel 20 and into and upwardly through the tubing 14. At the same time, fresh oil and gas will be drawn past the valve 40 and through the ports 36 into the chamber 32 to fill this chamber. If the pump is properly designed with the proper minimum in the clearance space the oil can be forced upwardly past the valve 46 in a very efficient manner at the pressure of 2000# per sq. in. and higher. It is believed clear that on the up-stroke of the working barrel the valve 40 will be open while the valve 42 will remain closed. On the same stroke the valve 44 will remain closed while the valve 46 will open as soon as the pressure within the chamber 34 has reached the amount of pressure in the oil column in the well tubing above that valve. On the down-stroke the valve 40 will remain closed while the valves 42 and 44 will open to allow passage of the fluid from the chamber 32 to the chamber 34, the valve 46 remaining closed throughout this stroke.

Obviously, the operation can be carried through more than two compression stages, and in Fig. 2 the 3-stage working barrel pump is very similar to the pump shown in Fig. 1, except that the fixed plunger 50 is provided with an upper extension 52 above the fixed pistons 54 and 56 and the working barrel 58 is provided with a lower internal ring or plunger 60 and an upper plunger 62. The fixed plunger is provided with 3 sets of ports 64, 66 and 68 communicating with three closed chambers 70, 72 and 74. At the upper and lower sides of the ports 64, 66 and 68 are respectively the valves 76 and 78, 80 and 82, and 84 and 86.

It will be noted that the operation of the three-stage pump is very similar to that described with reference to the pump shown in Fig. 1. On the up-stroke of the working barrel a mixture of oil and gas is drawn from the well into the chamber 70, while oil and gas is at the same time forced from the chamber 72 up into the chamber 74, the valves 76, 82 and 84 being open while the valves 78, 80 and 86 are closed. On the down-stroke the

oil and gas is compressed in the chamber 70 and is forced past the valves 78 and 80 into the chamber 72. The oil and gas mixture previously compressed into the chamber 74 is further compressed until the pressure reaches the pressure of the oil column above valve 86, at which time that valve opens allowing the mixture from chamber 74 to pass upwardly through the tubing string to the surface. Again, as was the case with the two-stage pump, if the pump is carefully designed so that there will not be undue clearance in the various chambers, the mixture of oil and gas can be taken at well pressure and compressed in substantially equal stages until it leaves the chamber 74 at pressure of say 2000# or greater.

In some instances it may be found desirable to allow some of the fluid to bleed back into the well past the standing valve in order to limit the maximum pressure to be developed above the standing valve 40 or 76. In Fig. 3 a combined standing and relief valve is illustrated, this valve being seated in a suitable pump lock 88. The valve comprises a vertically movable hollow member 90 having side guide wings 92 and openings at the top and bottom. The ball valve 94 is pressed against the inner top edge of the valve 90 by means of a suitable compression spring 96. When the oil or oil-gas mixture is drawn from the well the entire valve 90 will raise allowing the fluid to pass around the valve. When the valve 90 is closed, that is, in its lower seated position, in case the pressure above the valve should exceed a predetermined amount, the valve 94 will open thus bleeding some of the fluid back into the well.

Obviously, many modifications and variations of the invention as hereinbefore set forth may be made without departing from the spirit and scope thereof, and therefore only such limitations should be imposed as are indicated in the appended claims.

I claim:

1. A multi-stage well pump comprising a fixed tubular plunger having a pair of pistons secured in spaced relation along a central tube, means for securing the lower end of said tube in the tubing or casing of the well so that liquid to be produced will flow upwardly into the tube, a vertically reciprocable barrel movable on said pistons in telescoping relation to said fixed plunger, a ring member secured to the inner surface of said barrel between said pistons and forming with said pistons an upper and a lower chamber, said tube being provided with ports connecting the interior of the tube with each of said chambers and upwardly opening check valves disposed in said tube above and below each of said ports, the arrangement being such that on the upstroke of said barrel fluid will be drawn from the well into said lower chamber and fluid in the upper chamber will be forced into the tubular plunger and upwardly in the tubing, while on the down stroke fluid in the lower chamber will be forced through a portion of said tubular plunger into the upper chamber.

2. A multi-stage well pump comprising a stationary tubular plunger having a pair of enlarged pistons disposed in spaced relation along a concentric tube open at its upper and lower ends, means for securing the lower end of said tube in the tubing or casing of the well, a vertically movable working barrel surrounding said plunger and having friction engagement with said pistons, said barrel being provided near its midpoint with an inner movable plunger member disposed between said pistons and forming with said pistons a low pressure and high pressure chamber, a pair

of upwardly opening check valves in said tubes opposite said low pressure chamber, a second pair of upwardly opening check valves in said tube opposite said high pressure chamber, ports disposed between each pair of valves connecting the interior of said tubes with said low and high pressure chambers and means for reciprocating said barrel, so that on the up stroke of said barrel fluid will be drawn from the well into the low pressure chamber and fluid previously compressed in said high pressure chamber will be forced into the tubular plunger and upwardly in the tubing, while on the down stroke fluid in the low pressure chamber will be forced through a portion of said tubular plunger into the high pressure chamber.

3. A multi-stage well pump comprising a fixed tubular plunger having a pair of pistons secured in spaced relation along a central tube, means for securing the lower end of said tube in the tubing or casing of the well so that liquid to be produced will flow upwardly into the tube, a vertically reciprocable barrel movable on said pistons in tele-

scoping relation to said fixed plunger, a pair of annular upper and lower projections extending inwardly from said barrel into sliding engagement with said tube, and forming with said pistons low, medium and high pressure chambers, ports connecting the interior of said tube with each of said chambers and upwardly opening check valves disposed above and below each of said ports, the arrangement being such that on the up stroke of 10 said barrel fluid from the well below the pump will be drawn into the low pressure chamber and fluid from the medium pressure chamber will be forced through a portion of said tubular plunger into the high pressure chamber, while on the down stroke 15 of the barrel the fluid will be forced from the low pressure chamber through another portion of the plunger into the medium pressure chamber and fluid previously compressed in the high pressure chamber will be forced into the tubular plunger 20 and upwardly through the well tubing.
